UNITED STATES PATENT OFFICE.

BENJAMIN P. HAYES, OF KANSAS CITY, MISSOURI.

RIBBON-SHIFTING MECHANISM FOR ADDING OR LIKE MACHINES.

Original application filed February 27, 1920, Serial No. 361,743. Divided and this application filed July 11, 1921, Serial No. 483,833. Renewed May 8, 1925.

To all whom it may concern:

Be it known that I, BENJAMIN P. HAYES, a citizen of the United States, residing at Kansas City, in the county of Jackson and State of Missouri, have invented certain new and useful Improvements in Ribbon-Shift-
ing Mechanism for Adding or like Ma-
chines; and I do declare the following to be a full, clear, and exact description of the
invention, such as will enable others skilled
in the art to which it appertains to make
and use the same, reference being had to the
accompanying drawings, and to the figures
of reference marked thereon, which form a
part of this specification.

This invention relates to ribbon shifting mechanism for adding or like machines, the present application being a division of my co-pending application Serial No. 361,743,
for "adding machine."

In adding machines of the class to which my co-pending application belongs, amounts are entered in the machine through key board operation, registered on number wheels and printed upon a record strip, the printing on the strip being effected through type that are struck against an inked ribbon to effect an impression on the strip. When desired, a total of the entered amounts may be taken by a reverse operation, whereby the accumulation indicated on the register wheels is printed on the strip. In order to distinguish the total from the individual amounts, it is desirable to enter the total in a different color from that in which the individual amounts are printed. This may be accomplished through the use of a multi-colored ribbon, and it is the object of the present invention to shift the ribbon prior to the taking of the total, in order that the total may show in a distinguishing color.

In accomplishing this object, I have provided improved details of construction, the preferred form of which is illustrated in the accompanying drawings, wherein

Fig. 1 is a perspective view of my ribbon shifting mechanism, illustrated in connection with parts of an adding machine with which the shifting mechanism is assembled, and upon which it depends for its operation.

Fig. 2 is a detail, side elevation of the ribbon shift bar, illustrating its relation to the adding machine crank shaft and total key, and including the latch for retaining the

ribbon in shifted position while the total is being taken, the parts being shown in normal or non-shifted position.

Fig. 3 is a similar view of the same parts in shifted position, and

Fig. 4 is a transverse, vertical section of a part of the total key frame, illustrating the abutments for effecting movement of the shift bar.

Referring more in detail to the drawings,

1 designates the enclosing frame of an adding machine, and 2-3 the plates of a sub-frame upon which the record strip and part of the printing mechanism are mounted, the plates 2-3 having extension arms

4-5 rotatably supporting a platen 6, and having slots 7 at their upper ends, within which a shaft 8 is slidably mounted. On the shaft 8 are rollers 9 which are held toward the platen 6 by springs 10 that engage

the ends of the shaft 8 and are hooked over pins 11 of the arms 4-5 to yieldingly urge the rollers toward the platen and retain the record strip 12 snugly thereagainst, to form a smooth printing surface. The record strip

12 may be carried upon any suitable bracket, supported from the adding machine, but as this mounting forms no part of the present invention, it has not been illustrated in detail.

Rotatably mounted on platforms 14-15 are ribbon drums 16-17, upon which an inked ribbon 18 is wound, the ribbon being of the ordinary multi-colored type, having a black section 19 at the top and a red section 20 at the bottom. The inked ribbon

is preferably run over guide rolls 21-21' at opposite ends of the platen to extend the ribbon straight across the platen, and which are spaced apart sufficiently to permit vertical shifting movement of the ribbon without displacement from the guide rolls or drums.

Extending transversely across the machine at the bottom of the sub-frame is a bar 22, and pivotally mounted on said bar is a lever 23 which extends through vertical

slots 24 in the sub-frame plates 2-3, and is provided with an aperture 25. The lever 23 has a depending ear 26 at one end pivotally attached to the bar 22 by a stud 26', the aperture 25 being located at the opposite end

of the lever in order to provide an easy leverage for the limited shifting movement necessary for moving the inked ribbon from one printing position to the other. Pivotally mounted on the bar 23 by a stud 27 is a

yoke 28, the arms 29 of which have slotted upper ends 30 through which the inked ribbon 18 extends, so that when the lever is rocked on its pivot, the yoke arms are raised 5 or lowered and carry the ribbon with them to shift its position vertically, relatively to the platen and the type mechanism that is provided to cooperate therewith. The shifting parts just described are located at the 10 rear end of the adding machine, and positioned forwardly thereof is a total key post 32, adapted to slide in a slot 33 in the horizontal portion 34 of the guide plate 35, which is carried on the plate 1 of the main 15 machine through connection of the horizontal member with the frame, and by a stud 36 connecting the plate and frame at the lower end of the plate. The lower end of the plate 35 has a slot 37, in which is slidably mounted a stud 38 having an inner head 39 engageable by a pin 40 on the total key post. The lower end of the key post is also provided with a slot 40', through which the stud 36 projects to guide the key post 20 in its vertical movement. The total key post is normally retained in elevated position by a spring 41 connecting a hook 42 on the lower end of the post with a stud 43 on the guide plate 35. Pivots mounted on the 25 stud 38 is one end of a shift bar 45, of elbow construction, the rear body portion of which is inclined and overlies a stud 46 on a wing 47, rigidly mounted on the crank shaft 48 of the adding machine. The rear portion 49 30 of the shift bar 45 extends horizontally and terminates in a nose 50, adapted for projecting into the aperture 25 in the yoke shift lever 23, but is normally spaced therefrom so that it will not engage the lever unless 35 the bar is projected forwardly by manipulation of the total key post. With the arrangement described, the shift bar is positioned upon operation of the key post and the bar is moved upon operation of the 40 crank shaft to lift the ribbon shifting mechanism and raise the red portion of the inked ribbon into printing position. In order to retain the parts in this shifted position during a printing operation, I provide a latch, 45 comprising an arm 51, pivotally mounted on a stud 52 on the frame of the adding machine, and having a vertical slot 53 offset at the upper end of the arm to form a seat 54 for receiving a stud 55 on the shift 50 bar, that is adapted for travel in the slot when the bar is moved vertically. The shift bar is normally retained in inoperative position by a spring 56, connected with the stud 55 and with an eye 57, on a cross 55 bar 58 extending transversely between the main frame plates 1. The latch arm 51 is normally yieldingly held in position for seating the stud 55 in the seat 54 by a spring 60 connected with a pin 61 on the latch and 60 with a pin 62 on a pivotally suspended cam 63, which has a function in the adding machine proper, but has no part in the operation of the shifting mechanism except to form an anchor for the spring 60. Pivotally mounted on the stud 46, whereby the 70 shift bar is elevated, is a link 64 that is supported and guided on the pin 62 of the suspended cam 63, and is adapted for abutment against the pin 61 on the latch arm 51, so that when the crank shaft is returned to 75 complete its reciprocatory movement, the link may abut against the latch arm pin and shift the latch arm to unseat the stud 55 on the shift bar and permit the return of the bar and the ribbon yoke so that the black 80 portion of the ribbon is again presented to printing position.

Assuming the parts to be constructed and assembled as described, the operation is as follows: Ordinarily, the ribbon yoke is in 85 its lower position, as indicated in Fig. 1, so that the black portion of the ribbon is in printing position and the shift bar is held downwardly and rearwardly by the spring 56 so that when the crank shaft is operated, 90 the rear end of the shift bar moves up and down idly, relatively to the yoke lever. When a total is to be taken, the total key post is moved downwardly, shifting the bar 45 rearwardly so that its nose projects into 95 the aperture in the yoke, the total key post being held in lowered position by any suitable mechanism or latch construction, (not shown). When the shift bar is positioned, operation of the crank shaft causes the stud 100 46 on the wing 47 to engage the under edge of the bar and lift the bar. The nose of the bar, in engagement with the yoke lever, lifts the latter and the ribbon is shifted to 105 present the red portion thereof to printing position. As the shift bar is elevated, its stud 55 travels in the slot in the latch arm and when the stud reaches the top of the arm, the arm is moved forwardly to seat the stud so that the shift bar is held in elevated position, and in turn retains the ribbon yoke to hold the red portion of the ribbon in printing position. The parts are all 110 retained during a complete operation of the crank shaft, but as the shaft assumes its normal position, the end of the link 64 abuts against the pin 61 on the latch arm and moves the arm rearwardly to unseat the shift bar stud, so that the shift bar may be drawn back to normal position, thereby releasing 115 the ribbon yoke so that the latter may drop back and return the black portion of the ribbon to printing position.

It is apparent, therefore, that while the 120 ribbon shifting mechanism is operated from the crank shaft of the main machine, it does not perform its function except for total taking in that its movement is idle except when the controlling shift bar is set by the 125 total key and it is further apparent that 130

the ribbon is automatically returned after a single operation of the crank shaft to insure the printing of a successive individual amount in the distinguishing normal color.

5. What I claim and desire to secure by Letters Patent is:

1. Ribbon shifting mechanism for adding or like machines comprising, in combination with a total key and a main actuator, a ribbon guide, and means, normally disconnected from the ribbon guide, settable by the total key and operable by the actuator to shift the ribbon guide.

2. Ribbon shifting mechanism for adding or like machines comprising, in combination with a total key and a main actuator, a ribbon guide, means, normally disconnected from the ribbon guide, settable by the total key and operable by the actuator to shift the ribbon guide, and a latch for retaining said shifting means in functional position and operable by the main actuator to release the shifting means.

3. Ribbon shifting mechanism for adding or like machines comprising, in combination with a main actuator and a total key, a ribbon guide, and a shift bar, settable by the total key and operable by the main actuator, normally disconnected from but engageable 30 with the ribbon guide to shift the guide.

4. Ribbon shifting mechanism for adding or like machines comprising, in combination with a ribbon guide, a shift bar normally disconnected from the guide, means for setting the shift bar to co-operative relation with the guide, and a main actuator for effecting movement of the shift bar.

5. Ribbon shifting mechanism for adding or like machines comprising, in combination 40 with a ribbon guide, a shift bar normally disconnected from the guide, means for setting the shift bar to co-operative relation with the guide, a main actuator for effecting movement of the shift bar, a latch for retaining the shift bar in set position, and means operable by the main actuator to shift the latch and release the shift bar.

6. Ribbon shifting mechanism for adding or like machines comprising, in combination 50 with a total key and main actuator, the actuator comprising a crank having a laterally projecting stud, a ribbon guide, a shift bar engageable with the ribbon guide and bearing on the stud, the total key serving as a

fulcrum for the bar when the bar is actuated from the main actuator.

7. Ribbon shifting mechanism for adding or like machines comprising, in combination with a total key and crank shaft, a pivoted lever, a yoke on said lever adapted for engaging a printing ribbon, a normally idle shift bar operable by the total key for effecting its connection with the lever, and means on the crank shaft for operating the shift bar.

8. Ribbon shifting mechanism for adding or like machines comprising, in combination with a total key and crank shaft, the crank shaft having a wing and the wing having a laterally directed stud, a ribbon guide, a shift bar overlying the wing stud and normally yieldingly retained in engagement therewith, the shift bar operable by the total key against the tension of its yielding means for effecting co-operative relation of 75 the bar with the ribbon guide, and a latch for retaining the shift bar in functional position.

9. Ribbon shifting mechanism for adding or like machines comprising, in combination 80 with a total key and crank shaft, the crank shaft having a wing and the wing having a laterally directed stud, a ribbon guide, a shift bar overlying the wing stud and normally yieldingly retained in engagement 85 therewith, the shift bar operable by the total key against the tension of its yielding means for effecting co-operative relation of the bar with the ribbon guide, a latch for retaining the shift bar in functional position, and 90 means operable from the crank shaft for shifting the latch to release the shift bar.

10. Ribbon shifting mechanism for adding or like machines comprising, in combination 95 a pivoted lever, a yoke pivoted to said lever and adapted for engaging a printing ribbon, a floating shift bar yieldingly retained in non-functional position, a total key for moving the bar to functional position, a crank shaft having means engageable with the bar to rock the same, a latch engageable with the bar to retain the parts in shifted position, and means operable from the crank shaft for shifting the latch to permit return 100 of the shift bar and separation thereof from 105 the ribbon guide.

In testimony whereof I affix my signature.
BENJAMIN P. HAYES.
